(57) **CLAIM**

The ornamental design for a trailer tail light housing, as shown and described.

DESCRIPTION

FIG. 1 is a front perspective view of a first embodiment of a trailer tail light housing showing my new design, with the broken line showing for illustrative purposes only and forming no part of the claimed design.

FIG. 2 is a front view thereof.

FIG. 3 is a side view thereof.

FIG. 4 is a rear view thereof.

FIG. 5 is an opposite side view taken thereof.

FIG. 6 is a top view thereof.

FIG. 7 is a bottom view thereof.

FIG. 8 is a perspective view of a second embodiment.

FIG. 9 is a front view thereof.

FIG. 10 is a side view thereof.

FIG. 11 is a back view thereof.

FIG. 12 is an opposite side view thereof.

FIG. 13 is a top view thereof; and,

FIG. 14 view thereof.
